MONORAIL CAR

John K. Northrop, Pacific Palisades, and
John H. Northrop, La Canada, Calif.

Application November 16, 1954, Serial No. 33,116

Term of patent 14 years

(Cl. D66—1)

Fig. 2

Fig. 3

Fig. 4

Figure 1 is a three-quarter view in perspective of the monorail car showing our new design thereof;

Figure 2 is a side view of the monorail car shown in Figure 1;

Figure 3 is a front view of the monorail car shown in Figure 1; and

Figure 4 is a rear view of the monorail car shown in Figure 1.

The monorail is shown by means of broken lines for illustrative purposes only.

We claim:

The ornamental design for a monorail car, substantially as shown and described.
